UNITED STATES PATENT OFFICE.

WILLIAM J. RANTON, OF SYRACUSE, NEW YORK.

STEAM-GENERATOR.

SPECIFICATION forming part of Letters Patent No. 550,290, dated November 26, 1895.

Application filed March 26, 1895. Serial No. 543,202. (No model.)

To all whom it may concern:

Be it known that I, WILLIAM J. RANTON, of Syracuse, in the county of Onondaga, in the State of New York, have invented new and 5 useful Improvements in Steam-Generators, of which the following, taken in connection with the accompanying drawings, is a full, clear, and exact description.

This invention relates to improvements in 10 steam-generators of the class set forth in my previous patents, Nos. 484,339 and 489,689, issued, respectively, October 11, 1892, and January 10, 1893, and has for its object the production of a device which is particularly 15 effective in operation; and it consists, essentially, in the general construction and arrangement of the component parts of the generator, all as hereinafter more particularly described, and pointed out in the claim.

20 In describing this invention reference is had to the accompanying drawings, forming a part of this specification, in which like letters indicate corresponding parts in all the views.

25 Figures 1 and 2 are respectively transverse and longitudinal sections of my improved generator, the water-containing shell being shown in elevation at Fig. 1.

The water-containing shell A of my invention 30 is arranged in a substantially horizontal plane and is of suitable form, size, and construction. It is preferably circular in cross-section and may consist of separate sections suitably secured together, one of which is 35 usually provided with a steam-dome a. The opposite ends of the shell A are closed by heads a' a², engaged by braces a³, and having their outer edges provided with inwardly-turned flanges secured to said shell by suitable 40 fastening means a⁴. The central portions of the heads a' a² are formed with openings a⁵, aligned with each other and provided with inwardly-extending flanges. The upper and lower edges of the openings a⁵ are substantially flat and their ends are formed rounding. Directly beneath the openings a⁵ are manholes a⁶, which are closed by suitable 45 plates a⁷ and fastening means a⁸.

B is a fire-flue extending longitudinally 50 within the shell A, and having its opposite ends arranged within the openings a⁵ and secured by suitable fastening means b to the

inwardly-extending flanges of said openings. The central portion of the flue B may be supported by suitable braces b', although if the 55 shell A and the flue B are comparatively short these braces may be dispensed with. The flue B is formed with substantially flat upper and lower walls b² b³ and rounding longitudinal sides b⁴. Extending transversely across 60 the fire-flue B are a series of upright water-tubes B', having their opposite ends secured to the substantially flat upper and lower walls b² b³. The fire-flue B is of sufficient cross-sectional area to permit the passage of the 65 heated products of combustion without preventing their combustion, and the water-tubes B' are surrounded by said products of combustion and operate to heat the water passed therethrough.

In my aforesaid patents, Nos. 484,339 and 489,689, I have shown generators provided with lengthwise fire-flues, and in the practical operation of these generators I have observed that the water tends to remain unduly 75 quiet beneath the lower flat wall of the fire-flue, especially when the water-level is low. Consequently the efficiency of generators of this construction is not as high as would be the case were there a more positive circulation beneath their fire-flues. In my present 80 invention flues C extend lengthwise of the shell A beneath the opposite sides of the lower side b³ of the fire-flue B, and their opposite ends are secured to the end heads a' 85 a² at opposite sides of the manholes a⁶. The flues C are of considerably less cross-sectional area than the fire-flue B and are of suitable number, and, as they are on opposite sides of the manholes, entrance within the shell A is 90 permitted for enabling securement of the water-tubes B'. The flues C produce a circulation of the water in the shell A beneath the fire-flue B, and greatly add to the efficiency 95 of my generator.

D is the outer casing for the shell A, and, as will be obvious to one skilled in the art, this casing is of any desirable form, size, and construction. It is preferably formed with a combustion-chamber d arranged beneath the 100 front end of the shell A, a fire passage d' extending from the chamber d beneath the opposite end of the shell A and provided with an upturned end d², projecting above the rear

ends of the flues C B, and a draft-chamber d^3 arranged in front of the opposite ends of said flues C B. The draft-chamber d^3 is provided with a suitable outlet d^4 and may be formed 5 with a removable door d^5 , the construction of which it is unnecessary to herein further describe.

The operation of my invention will be readily understood upon reference to the foregoing description and the accompanying drawings, and it will be obvious to one skilled in the art that it is particularly effective in operation.

Having thus fully described my invention, 15 what I claim as new, and desire to secure by Letters Patent, is—

In a steam generator, the combination of a water containing shell A of substantially circular cross section provided with substantially circular end heads a' a^2 having openings a^3 in their central portions aligned with each other, and manholes a^6 arranged beneath the openings a^5 , a fire flue B within the shell A having its opposite ends secured in the open-

ings a^5 , flues C within the shell A extending 25 lengthwise thereof beneath the fire flue B on opposite sides of the manholes a^6 and having their opposite ends secured to the heads a' a^2 , and an inclosing case A provided with a combustion chamber d beneath the front end of 30 the shell A, a fire passage d' extending beneath the shell A from the combustion chamber to the opposite end of the shell A and formed with an upturned end d^2 arranged at the rear of said shell A and projecting above 35 the rear ends of the flues B C, and a draft chamber d^3 arranged in front of the opposite ends of the flues B C, substantially as and for the purpose specified.

In testimony whereof I have hereunto signed my name, in the presence of two attesting witnesses, at Syracuse, in the county of Onondaga, in the State of New York, this 7th day of March, 1894.

WILLIAM J. RANTON.
